(57) **CLAIM**

The ornamental design for a dolphin clamp, as shown and described.

DESCRIPTION

FIG. 1 illustrates a top plan view of the dolphin clamp; FIG. 2 illustrates a left side elevation view of the dolphin, the right side a mirror image thereof; and,

FIG. 3 illustrates a bottom view of the dolphin clamp; FIG. 4 illustrates a front elevation view of the dolphin clamp; and,

FIG. 5 illustrates a rear elevation view of the dolphin clamp. The broken lines in the figures depict portions of the dolphin clamp that form no part of the claimed design.
